UNITED STATES PATENT OFFICE.

PHILIP WUEST, JR., OF PHILADELPHIA, PENNSYLVANIA, ASSIGNOR TO THE AUTO-MANUAL PIANO ACTION COMPANY, OF PHILADELPHIA, PENNSYLVANIA, A CORPORATION OF NEW JERSEY.

RHYTHM-INDICATOR FOR MECHANICAL MUSICAL INSTRUMENTS.

No. 875,974.

Specification of Letters Patent.

Patented Jan. 7. 1908.

Application filed October 19, 1904. Serial No. 229,161.

To all whom it may concern:

Be it known that I, PHILIP WUEST, Jr., of Philadelphia, in the State of Pennsylvania, have invented certain new and useful 5 Improvements in Rhythm-Indicators for Mechanical Musical Instruments, whereof the following is a specification, reference being had to the accompanying drawings.

My invention is applicable to instruments 10 provided with automatic playing mechanism comprising a series of levers in operative relation to sounding devices, such as the strings of a piano, and arranged to be actuated in any predetermined sequence by 15 means of independent pneumatic mechanism controlled by a note sheet or web of perforated paper, which is progressed with respect to a pneumatic tracker bar provided with a series of apertures corresponding with 20 the series of pneumatic mechanisms.

My invention relates particularly to an indicating device arranged to enable the operator to precisely ascertain the rhythm of the measures or other time divisions of the 25 musical composition represented by a note sheet in operative relation to said tracker bar, and thus be advised of the exact instant in which to manipulate the expression device of the instrument. Said expression device 30 may be of any desired form and operated in any desired manner. My invention may be employed with particular advantage in conjunction with a note sheet comprising lines extending transversely with respect to its 35 length, which lines are located at the regions of the note sheet corresponding to the pulses in the musical composition, the distance between the adjoining rhythm indicating marks, measured longitudinally of the sheet, 40 being varied in accordance with the tempo of the composition.

My invention also utilizes such an arrangement of the rhythm symbols transversely of the note sheet that they also indicate the 45 correct transverse position of the tempo controller, for instance, either by an interruption in the transverse length of said lines, or by a symbol associated therewith, manifesting such position.

50 As hereinafter described, my invention includes a tempo controlling mechanism having a movable member provided with a panel, of glass or other suitable material, forming a transparent field bearing a dot or

other index mark, without apparent supporting connection with said mechanism, so as to afford a clear view of the precise relation of said index mark to the rhythm symbols upon the note sheet with which it is to be employed.

My invention comprises the various novel features of construction and arrangement hereinafter more definitely specified and claimed.

In the accompanying drawings, Figure I, 65 is a front elevation of a portion of an instrument of the class contemplated, embodying a convenient form of my invention. Fig. II, is a transverse sectional view of said device, taken on the line II, II, in Fig. I. 70

In said figures,—1, is that portion of the instrument frame known as the music box, supporting the tracker bar 2. The perforated web or note sheet 4, is arranged to be progressed downwardly over said tracker bar 75 2, from the roll 6, to the roll 7, by rotation of the shaft 9, of said roll 7. It is to be understood that the instrument comprises a variable speed motor for effecting such rotation and that the speed of such rotation may be 80 controlled by movement of the rod 12. For instance, if the motor is a pneumatic one, said rod may connect with a valve controlling the area of an air port through which said motor is actuated. However, it is to be 85 understood that the arrangement is such that when said rod 12, is moved to the right in Fig. I, the speed of progression of said web 4, is increased, and when said rod is moved in the opposite direction said speed is 90 decreased. Said rod 12, is connected by the pivot 13, with the controller slide bar 14, which is arranged to reciprocate in the bearings 15, and conveniently provided with the operating handle 17, having the index point 95 18, arranged to traverse the scale 20, supported by the cross bar 21, in said box I. Said scale 20, is conveniently provided with graduations corresponding with those upon an ordinary metronome, and the arrangement is such that when said index point 18, registers with any one of said graduations, the speed of progression of the note sheet 4, is in substantial correspondence with the rate as designated by a metronome. Said 100 handle 17, is conveniently mounted on the cross head 22, which is secured to the bar 14, by the set screw 23, and has its rear end ar-

anged to slide in the bearing 24, on said box 1. Said cross head 22, carries the arm 26, provided with the screw stud 27, arranged to detachably and adjustably engage the shank 28, of the index frame 29, which supports the panel 30, forming a transparent field bearing the index dot 31. Said index frame 29, is preferably provided with pointers 33, at the opposite sides thereof, in alinement 10 with said index dot 31, so that the precise instant when any one of the rhythm symbols or lines 35, on said web 4, registers with said dot 31, may be accurately recognized by the operator, and the expression device of the 15 instrument be controlled in accordance therewith.

As shown at the left hand side of Fig. I, the lines 35, may be provided with circular symbols 36, indicating variations in the 20 tempo corresponding with the respective pulses, by the numerals marked in the circles corresponding with the numerals on the scale 20; or, as indicated at the upper portion of Fig. I, symbols 38, indicating variations in 25 the tempo contemporaneous with the respective pulses or the rhythm may be located in the lines 35, transversely with respect to the sheet 4, to determine the corresponding position of the index dot 31, and the tempo 30 controlling mechanism to which it is connected, indicated by the numerals marked within the circles of said symbols. However, said symbols may be omitted and the proper position of the index dot 31, be indicated by the termination of the transverse lines 35, at different regions in the transverse width of the sheet 4, in definite relation to the corresponding position of said tempo controlling device, determined by said dot 31, or 40 there may be interruptions in the length of said lines 35, in correspondence with the desired position of said dot 31.

Although I have shown the transparent panel 30, as of uniform thickness throughout 45 its extent, it is to be understood that its surface may be curved to constitute it a lens capable of rendering the rhythm indicators more conspicuous during their conjunction therewith.

50 It will be noted that in my invention the indicating device, whereby the symbols upon the moving sheet can be recognized in their true relation to the progress of the sheet, is combined with a moving member of the 55 tempo controlling mechanism so as to directly accompany the manual movement of the latter. Ordinarily, the features of tempo and rhythm are so close as to substantially coincide, and even when this is not absolutely 60 the case, the relation between them may be said to be practically constant. Hence the organization characteristic of my invention permits the operator to concentrate his attention to the best advantage, the movement 65 of the eye as it follows the shifting of the

indicator, accompanying the movement of the hand, without conscious effort, thus facilitating the recognition of the symbols, as they approach and coincide with the critical point of the indicator.

70 It will also be noted that the rhythm symbols are located transversely of the sheet in proper relation to the tempo corresponding to that particular portion of the selection being rendered, while their location longitudinally of the sheet corresponds to the pulses or rhythm. Thus, in watching for the rhythm symbols, and moving the handle connected with the panel 30, to cause the dot 31, to register with said symbols respectively 75 as they move along, the operator incidentally varies the tempo in accordance with the selection, while ascertaining the exact instant at which to manipulate the expression device. 80

85 I do not desire to limit myself to the precise details of construction and arrangement herein set forth, as it is obvious that various modifications may be made therein without departing from the essential features of my 90 invention.

I claim:

1. In a mechanical musical instrument, the combination with a note sheet having symbols spaced longitudinally of said sheet, 95 corresponding to the rhythm and transversely of said sheet in a definite relation to the predetermined position of the tempo controller; of means for progressing said sheet; a controller for varying the rate of movement of said sheet; and a transparent panel carried by said controller and bearing an index mark adapted to be moved to register with the symbols on said sheet, whereby the operator of the instrument may simultaneously vary the tempo and ascertain the precise moment for operating the expression device. 100

110 2. In a mechanical musical instrument, the combination with a note sheet having transverse lines spaced longitudinally thereon corresponding to the rhythm, said lines being provided with symbols located transversely of the sheet in a definite relation to the predetermined position of the tempo controller; of means for progressing said sheet; a controller for varying the rate of movement of said sheet; and a transparent panel carried by said member and bearing an index 115 mark adapted to be moved to register with the symbols on said sheet, whereby the operator of the instrument may simultaneously vary the tempo and ascertain the precise moment for operating the expression device. 120

125 3. In a mechanical musical instrument, the combination with a note sheet; means for progressing the same; a movable member for controlling the rate of movement of said sheet; an index frame connected with said member comprising opposed pointers; 130

and a transparent panel supported by said frame and bearing an index mark in alignment with said pointers, substantially as set forth.

- 5 4. In a mechanical musical instrument, the combination with a note sheet having symbols spaced longitudinally thereof corresponding to the rhythm of the selection, said symbols being located transversely of said 10 sheet in a definite relation to the predetermined position of the tempo controller; of means for progressing said sheet; and a con-

troller for varying the rate of movement of said sheet provided with means coöperating with said symbols to enable the operator to 15 ascertain the precise instant at which an accent or beat occurs.

In testimony whereof I have hereunto signed my name at Philadelphia, Pennsylvania, this 17th day of October, 1904.
